UNITED STATES PATENT OFFICE.

JOHN B. SMITH, OF SUNAPEE, ASSIGNOR TO CHARLES N. FREEMAN AND DAVID W. O'NEIL, OF CLAREMONT, NEW HAMPSHIRE.

MACHINE FOR MAKING BRACKETS FOR TELEGRAPH-INSULATORS.

SPECIFICATION forming part of Letters Patent No. 278,618, dated May 29, 1883.

Application filed September 2, 1882. (No model.)

To all whom it may concern:

Be it known that I, JOHN B. SMITH, of Sunapee, in the county of Sullivan and State of New Hampshire, have invented a new and Improved Machine for Making Brackets for Telegraph-Insulators; and I do hereby declare that the following is a full, clear, and exact description of the same, reference being had to the accompanying drawings, forming part of this specification, in which—

Figure 1 is a perspective view of the entire machine. Fig. 2 is an elevation of the rear side of the same. Fig. 3 shows a detail view of a completed bracket. Fig. 4 shows a detail view of the blank or piece of material from which two brackets are formed, the dotted lines indicating the general outline of the brackets formed from said blank. Fig. 5 is a vertical transverse section taken through the line $\alpha\alpha$, Fig. 2; and Fig. 6 is a plan view of the central parts of the machine.

The object of my invention is to provide a machine for making wooden brackets for telegraph-insulators; and to this end it consists in a novel organization of parts for holding the blank and simultaneously turning its two ends to form two brackets, as will be hereinafter more fully described.

In the drawings, A represents the main framework, upon which are mounted devices for feeding and holding the blank while its ends are being turned, and also two independently-rotating mandrels having a reciprocating motion and bearing funnel-shaped cutter-heads, which are advanced upon the ends of the blank to turn the same into shape.

I will first describe the means for feeding and holding the blank in the line of the cutter-heads.

B is a guide-frame arranged about the middle of the frame A, on top of the same, and in transverse relation thereto. In grooves in this guide-frame is arranged the sliding feed-table C, which reciprocates transversely to the main frame. On this table are arranged two raised bars or projecting lugs, $a a$, whose shoulders or ends next to the cutter-heads are arranged upon a diagonal line. For giving a reciprocating motion to this table a connecting-rod, D, Fig. 1, is jointed at one end to the lower side of the same, and at the other end is jointed

to a vertical lever, E, fulcrumed in the middle to an offset from the main frame. The lower end of this lever is jointed to a horizontal connecting-rod, F, which is jointed to the lower end of a lever, G, Fig. 5, fulcrumed at its upper end to the frame A, and having near its middle a pin or friction-roller, b, that traverses a cam-groove, c, in the cam-plate H. This cam-plate is rigidly attached to a revolving horizontal shaft, I, arranged longitudinally with frame A in bearings upon the side thereof. This shaft is provided with a gear-wheel, J, Fig. 2, which receives motion from a pinion, K, on a short shaft, L, upon which short shaft is also arranged a driving-pulley, to which motion may be communicated by a belt for the purpose of giving a slow rotation to the long shaft I, and when the latter is rotated it imparts, through the cam-plate H, lever G, connecting-rod F, lever E, and connecting-rod D, a reciprocating motion to the feed-table.

Just above the feed-table, and in the vertical line of the cutter-heads, is a T-shaped clamp, U, Fig. 6, whose head-piece is set slightly diagonal to the axial line of the cutters, for the purpose hereinafter described, and which head-piece has downwardly-projecting stops $d d$. The shank portion of the T-shaped clamp is rigidly keyed to a rock-shaft, M, held in bearings in upright supports N N from the main frame. This rock-shaft is provided with a crank-arm, O, Fig. 1, one end of which is connected to a vertical rod, P, which at its lower end is jointed to the middle of a horizontal lever, Q. This lever Q is fulcrumed at one end upon an upright support, R, rising from the lower portion of the main frame, and at its other end it rests beneath a cam, S, Fig. 2, on the longitudinal shaft I, being held up to engagement with said cam by a spring, T, so that as this shaft I revolves it imparts a rocking motion to shaft M, and the clamp U is made to oscillate therewith, moving down at the proper time to hold the blank while being turned, and rising therefrom to release it when finished.

The devices for turning the ends of the blank consist of two funnel-shaped cutter-heads, e e, having knives arranged after the manner of the ordinary pencil-sharpener. These cutter-heads are arranged an equal dis-

tance from the feed-table, on each side of the same, and they have both a rotary and a right-line movement. Both being geared precisely alike, it will only be necessary to describe the connections of one of them. Each cutter-head is located on the inner end of a revolving shaft, *f*, provided with a drive-pulley, *g*. This shaft is journaled in a metal frame, *i*, Figs. 1 and 2, arranged upon the top of frame *A*, and 10 swivels at one end in a head, *j*, to the lower portion of which is attached a sliding guide-rod, *k*, arranged in parallel position beneath the shaft *f*, and sliding in bearings in the frame *i*.

15 To the head *j*, which forms the bearing for the outer end of the revolving shaft, is jointed the upper end of a lever, *V*, fulcrumed at its bottom to the end of the machine, and having about its middle a roller, *l*, that enters a cam-groove, *m*, in a cam-plate, *W*. This cam-plate is fixed on a short transverse shaft, *X*, at the end of the machine which is connected to the longitudinal shaft *I*, and derives motion therefrom through the bevel-gears *n*. This cam-plate, with its cam-groove, then, it will be seen, 25 serves to impart to the revolving shaft bearing the cutter-head a longitudinal reciprocating movement, bringing each cutter-head against the end of the blank, and then withdrawing it, the curve of the cam-grooves being such that said cutter-heads are gradually projected toward the blank, then quickly withdrawn, and then, after an interval of rest to permit the turned blank to be removed, are 30 again moved forward for a repetition of the action.

For giving rotary motion to the revolving cutter-heads, the pulleys *g* are belted to drums *Y Y'* on lower horizontal shafts, *Z Z'*, on which 40 are drive-pulleys *p p'*, which are belted to any suitable driving mechanism, the drums having a periphery wide enough to accommodate the belt in the lateral movement of the pulley *g*. Two separate shafts, *Z Z'*, with pulleys and 45 drums, are here employed for the purpose of giving to the cutter-heads an opposite revolution, so that the cutting strain of one shall neutralize the cutting strain of the other, and the blank will not be so liable to become 50 twisted or displaced. On each side of the feed-table are gage-strips *r r*, which serve to adjust the position of the blank on the table.

The operation of the machine is as follows: A block or blank of the form shown in Fig. 4 55 is placed upon the feed-table in front of the lugs or bars *a a*. The machine then being in operation and the parts properly timed, the feed-table advances and simultaneously the clamping-bar *U* descends. As soon as the 60 blank is in the line of the cutter-heads it strikes the stops *d d* of the clamping-bar, and

simultaneously the clamping-bar bears upon the top of the blank and holds it firm. Then the cutter-heads advance upon the ends of the blank, and, rotating in opposite direction, 65 turn off the portion marked 22 in Fig. 4, leaving the blank in condition to form two brackets by being divided through the diagonal dotted line, forming two brackets of the general shape shown in Fig. 3, upon which a screw-thread is afterward cut. The cutter-heads, after having done their work, retire quickly, and pause a moment while the turned blank is being dislodged and a new one inserted, after which the same action takes place. 75

In order to make two brackets out of the piece shown in Fig. 4, it is necessary that the blank should be turned off at its ends more upon one side than it is upon the other, as at 22, and for this purpose the blank must not 80 be placed exactly in the line of the axis of the cutters, but somewhat obliquely thereto; hence will be seen the necessity for arranging the lugs *a a* and the stops *d d* with their faces obliquely to the said axis of the cutter-heads. 85

Having thus described my invention, what I claim as new is—

1. The sliding feed-table with raised lugs or bars *a a*, in combination with the clamping-bar having stops *d d* and the revolving and reciprocating cutter-heads, substantially as and for the purpose described. 90

2. The sliding feed-table with raised lugs or bars *a a*, in combination with the clamping-bar having stops *d d*, for the purpose of advancing the blank, defining its position, and holding it firm, as shown and described. 95

3. The combination, with the revolving cutter-heads, the reciprocating table having lugs *a a*, and the oscillating clamping-bar *U*, having stops *d d*, of the rock-shaft *M*, having arm *O*, rod *P*, lever *Q*, cam *S*, spring *T*, and main shaft *I*, as and for the purpose described. 100

4. A machine for turning brackets for insulators, consisting of a reciprocating table with lugs *a a*, and clamping-bar with stops *d d*, arranged substantially as described, for feeding and holding the blank in an inclined position, combined with two reciprocating cutter-heads rotating in opposite directions and acting simultaneously upon opposite ends of the blank to neutralize the cutting strain, as described. 105

5. The feed-table having lugs *a a*, and the clamp having stops *d d*, both said lugs and stops being arranged with their faces in a line diagonal to the cutter-head axis, and combined with said cutter-head, substantially as shown and described. 110
